Eli T. Starr,

Baldwin, Hopkins, & Peyton.

UNITED STATES PATENT OFFICE.

ELI T. STARR, OF PHILADELPHIA, PENNSYLVANIA, ASSIGNOR TO JAMES W. WHITE, J. CLARENCE WHITE, AND H. M. LEWIS, ALL OF SAME PLACE, AS TRUSTEES UNDER THE WILL OF SAMUEL S. WHITE, DECEASED.

DENTAL-ENGINE HAND-PIECE.

SPECIFICATION forming part of Letters Patent No. 231,734, dated August 31, 1880.

Application filed July 10, 1880. (Model.)

To all whom it may concern:

Be it known that I, ELI T. STARR, a citizen of the United States, residing in the city and county of Philadelphia, in the State of Pennsylvania, have invented certain new and useful Improvements in Dental-Engine Hand-Pieces, of which the following is a specification.

My invention relates to the class of hand-pieces for dental engines in which the operating-tool is secured in the socket of the spindle tool-holder or chuck by means of a spring-jaw or split tool-fastening carried by the chuck in its revolutions.

15 The best hand-pieces of this type known to me are those exemplified in the Letters Patent granted to Re Qua, January 22, 1878, as No. 199,469; Cushing, August 5, 1879, as No. 218,239, and Phillips, September 23, 1879, as 20 No. 219,873.

My invention constitutes an improvement more especially upon the hand-pieces of Cushing and of Phillips, and has for its object the production of a superior instrument.

25 My invention consists in certain new combinations and organizations of devices, which are recited at the end of the specification.

In the accompanying drawings, which illustrate the best way now known to me of embodying my improvements, Figure 1 is a longitudinal central section through the hand-piece. Fig. 2 is a similar section through a portion of the hand-piece with some of the parts in positions different from that depicted 35 in Fig. 1. Fig. 3 is a transverse section through the device on the line 3 3 of Fig. 2, and Figs. 4 and 5 are similar transverse sections on the lines 4 4 and 5 5, respectively, of Fig. 1.

The casing A of the hand-piece is preferably 40 composed of four tubular sections—that is, of a nose or end section, a, preferably of hardened steel; of a handle-section, a', which surrounds the tool-holder or chuck B and forms a sheath for it, said section being grasped usually between the fingers and thumb somewhat in the manner of holding a pen or pencil, to guide the operating-tool and hold it to its work; of a section, a², preferably of hard metal, to which the handle-section is connected by

screw-threads, so as to permit said handle-section to be readily detached to uncover the tool-holder or chuck for oiling, &c., and of a shank-section, a³, connected with the said section a² by screw-threads, so as to permit ready separation of said sections in order to obtain access to the interior of the hand-piece.

The tool-holder or chuck B has its bearings at front in the nose or section a of the casing and in rear of the hard-metal section a², and is given a rapid revolving motion upon its longitudinal axis in said tubular bearings by a flexible power-conveyer or shaft of the usual or any approved construction.

The shank-section a³ of the casing is preferably connected with the outer or free end of a flexible sheath or tube, which envelops the flexible power-conveyer to protect it—for example, as in the well-known S. S. White dental engine, and as shown in the reissued Letters Patent granted to N. Stow, March 4, 1879.

I have deemed it unnecessary to show either the flexible driving-shaft or its flexible enveloping-sheath, as they form no part of the subject-matter herein claimed.

The tool-holder is locked from endwise movement in the casing by annular shoulders, which abut against corresponding shoulders formed on the interior of the casing. The annular shoulder b at the front end of the tool-holder constitutes the pull-bearing, preventing endwise movement of said tool-holder in an outward direction when a pulling or draw cut is being made with the operating-tool; and the annular shoulder b', formed by the milled collar b², near the rear end of the tool-holder, 80 constitutes the push or thrust bearing, preventing endwise movement of the tool-holder in an inward direction when a pressure or thrust cut is being made with the tool.

The tool-holder or chuck is tubular. A shaft, C, is passed through the chuck from end to end, the front end of which shaft is longitudinally split, so as to form spring clamping-jaws, and is socketed for the insertion of the shanks of the operating-tools, which are 95 clamped or fastened in the socket by the compression of the clamping-jaws.

The ends of the members of the split or

spring-jawed tool-fastening protrude a short distance in front of the end of the chuck and terminate in a slightly-enlarged tapering head, so that when drawn within the mouth of the tool-holder the said members will be closed together or compressed, while when moved out from said mouth they will spring apart, expand, or move laterally, as is common in this form of tool-fastening, and as fully described in the patents hereinbefore referred to.

In order to positively move the said shaft C endwise within the tool-holder or chuck to compress or release the clamping-jaws, (the tool-holder being locked from endwise movement, as before described,) the said shaft at its rear end, which is extended through and beyond the rear end of the chuck, is provided with a cup-piece, D, fitted upon the shaft and locked from endwise movement thereon by two collars, d d' , fixed to the shaft, the front enlarged end of said cup-piece being internally threaded to receive the externally or male threaded butt-end of the chuck, so that by turning said chuck on its axis to screw it in or out of said cup, said cup, and with it the shaft C, will be caused to move endwise to clamp or release the tool-fastening, according to the direction of rotation of the chuck.

In order to prevent the said cup-piece from turning when it is desired to operate the tool-fastening, while permitting it to move endwise with said fastening as the chuck is turned by the milled collar b^2 , which is grasped by the fingers through openings c c' in the opposite sides of the casing when the thimble or sleeve E is drawn back to expose said openings and collar, a pin or screw, f , is passed through said sleeve, and its end engages with one of a series of longitudinal peripheral grooves, d^2 , formed on the cup-piece D. (Clearly shown in Figs. 1, 2, and 3.)

The sleeve E is permitted to be moved backward and forward on the casing to engage and disengage its screw f from the cup-piece by means of a longitudinal slot, g , in the casing sections a^2 a^3 , while it is prevented from turning relatively to said casing by said screw, whereby it is obvious that if the sleeve is drawn back to engage its screw with one of the grooves of the cup-piece D said cup-piece will be locked from rotation independently of the casing, while the chuck may be turned by its milled collar in order to reciprocate the cup-piece and shaft C in the chuck.

In operation, of course the sleeve will be in its forward position, as shown in Fig. 1, to cover the openings c c' , and so as not to in-

terfere with the rotation of the shaft and chuck in the casing in driving the operating-tool.

Fig. 2 shows the sleeve E as drawn back, with its screw locking the cup-piece D from turning, to permit the milled collar b^2 to be turned to screw the cup-piece and shaft forward to release the tool-fastening.

The socket of the tool-fastening is preferably provided with a tangential pin, h , or with a suitable lug to engage a notch in the tool-shank, so as to lock said tool firmly in the socket and enable it to be driven firmly and positively without relying upon the tool-clamping devices alone for the purpose.

It will be noticed that a chamber, i , is formed at the nose of the hand-piece forward of the front end of the tool-holder, and this is for the purpose of arresting the entrance of extraneous matter to the bearing of the chuck, and for preventing the escape of lubricating-oil to the outside of the hand-piece. This feature is the invention of Phillips, whose patent has been above referred to.

I claim as my invention—

1. The combination, substantially as hereinbefore set forth, of the casing, the tubular tool-holder turning in bearings therein, the shaft passing through said tool-holder and having its front end split to form tool-locking jaws, the cup-piece fitted on said shaft so as to be incapable of endwise movement thereon and connected with the tool-holder by a screw-connection, and the sliding thimble to lock said cup-piece from turning without preventing its endwise movement while exposing the chuck for operation to enable the tool-locking shaft to be reciprocated.

2. The combination, substantially as hereinbefore set forth, of the casing having openings in its side, the tubular chuck mounted in said casing and having a collar to turn it opposite said openings, the shaft extended through said chuck having a socket and clamping-jaws at its front end, the pin or lug in the socket of said chuck to engage the locking-notch of a tool-shank, the cup-piece on said shaft connected with the chuck by a screw-connection, and the sliding thimble which locks said cup-piece from turning while exposing the collar by which the chuck is turned to reciprocate the tool-lock.

In testimony whereof I have hereunto subscribed my name.

ELI T. STARR.
